UNITED STATES PATENT OFFICE.

HARRY BRADLEY ROWAN, OF NORTH ATTLEBORO, MASSACHUSETTS, ASSIGNOR TO WHITING & DAVIS COMPANY, A CORPORATION OF MASSACHUSETTS.

DESIGN FOR A MESH BAG.

Application filed September 25, 1924. Serial No. 10,900. Term of patent 14 years.

To all whom it may concern:

Be it known that I, HARRY BRADLEY ROWAN, a citizen of the United States, residing at North Attleboro, Bristol County, Massachusetts, have invented a new, original, and ornamental Design for Mesh Bags, of which the following is a specification, reference being had to the accompanying drawings forming part thereof.

The figures are a front view and a side view of a mesh bag showing my new design.

I claim:

The ornamental design for a mesh bag as shown.

HARRY BRADLEY ROWAN.
